PAGE 2

Fig. 3

Fig. 4

Fig. 5

Fig. 6

Fig. 1 is a perspective view of one side of an imprinting machine, showing my new design;

Fig. 2 is a perspective view of the side of the imprinting machine opposite that shown in Fig. 1;

Fig. 3 is a perspective view showing one end of the imprinting machine;

Fig. 4 is a perspective view showing the end of the imprinting machine opposite that shown in Fig. 3;

Fig. 5 is a perspective top view of the imprinting machine; and

Fig. 6 is a perspective view showing the head of the imprinting machine in open position relative to the base.

I claim:

The ornamental design for an imprinting machine, substantially as shown.
